UNITED STATES PATENT OFFICE.

JOSEPH P. CLEAL, OF TORONTO, ONTARIO, CANADA, ASSIGNOR TO THE NATIONAL CASH REGISTER COMPANY, OF DAYTON, OHIO, A CORPORATION OF OHIO, (INCORPORATED IN 1906.)

CASH-REGISTER.

1,047,751.

Specification of Letters Patent. Patented Dec. 17, 1912.

Application filed June 18, 1906. Serial No. 322,251.

To all whom it may concern:

Be it known that I, JOSEPH P. CLEAL, a citizen of the United States, residing at Toronto, in the Province of Ontario, Canada, have invented certain new and useful Improvements in Cash-Registers, of which I declare the following to be a full, clear, and exact description.

This invention relates to cash registers and has for its object to provide a machine especially for use in canceling so called bundle ticket or delivery slips.

In many commercial houses, for example, a sale slip is made out in duplicate, one copy being filed and the other copy being given to the customer who thereupon takes the purchase away with him or her. This system in practice is fairly satisfactory in cases where the customer does not desire the bundle delivered by the store but in cases where a delivery is to be made as by wagon, opportunity is given to the clerks to defraud the proprietor. This duplicate slip system is also used in connection with a well known type of cash register in which the machine prints the amount of the sale in two places on a slip which is then severed into two parts, one of which is retained in the machine as a voucher, the other being ejected and serving as a receipt. In the use of such machines in connection with a sale for immediate delivery the amount received must be added in on the machine in order to print on the slip, without which the bundle will not be wrapped. In the case of a sale with future delivery an operation of the machine is made and the sale slip attached to the bundle which is then taken to a room to be wrapped, and in such cases some means of authorizing the wrapping and sending out of the package must be provided.

My invention aims to provide means for authorizing such wrapping and delivery and to this end I employ a delivery slip or bundle ticket longer than the usual sales slip, which is adapted to have printed thereon such matter as the word "Paid" and the date or other desired matter. The portion of the slip bearing this matter may be detached and pasted or otherwise attached

to the bundle, and will be understood as authorizing its delivery.

In particular this invention aims to improve the machine shown in application 55 bearing Serial Number 160,416, filed June 6, 1903, by Thomas Carroll. The machine shown in said application is designed to make two printing impressions on a sale slip, one part of the slip being retained in 60 the machine after the impression is made and the other part being taken from the machine after printing.

For use in connection with future delivery sales I provide a longer bundle ticket or 65 delivery slip than the usual sale slip and means are provided for marking this slip with a record of any desired matter e. g. the word "Paid" and the date. The machine includes an extra printing device so 70 located as not to operate on the usual sale slip as such slip is not long enough to reach the extra printing device but when a longer bundle ticket is inserted in the machine the above stated additional impression will be 75 made.

With these and incidental objects in view, the invention consists in certain novel features of construction and combination of parts, the essential elements of which are 80 set forth in appended claims and a preferred form of embodiment of which is hereinafter specifically described with reference to the drawings which accompany and form part of this specification.

Of said drawings: Figure 1 is a section through the machine. Fig. 1^a is a detail view of the testing device. Fig. 2 is an elevation of one end of the machine showing the operating device for the auxiliary printer. Fig. 2^a is a detail view of the auxiliary printer in normal position. Fig. 2^b is a similar view showing the auxiliary printer in printing position. Fig. 3 is a view of the operating mechanism shown in Fig. 2 in a partially operated position. Fig. 4 is an elevation of the printer setting devices. Fig. 5 is a sectional view of same taken approximately on line 5—5 of Fig. 4. Figs. 6 and 7 are respectively side and 100 edge views of a Geneva stop mechanism for operating the auxiliary printer.

The machine to which I have shown my invention as adapted, is designed for use especially in commercial establishments in which it is desired to stamp a sales slip for each transaction entered in the machine.

The machine in general comprises a plurality of setting levers one for each denomination which are differentially adjustable over a scale. The adjustment of these levers serves to position a set of printing wheels. Mechanism is provided for supporting a sale slip and for giving the slip an impression of the amount from the printing wheels. The slip is then fed farther into the machine and a second impression made on another part of the slip. A knife serves to sever the part bearing the first impression which is retained in the machine and the part bearing the second impression is then fed back out of the machine. I have added to this mechanism an auxiliary printing device bearing a number or the date or any desired matter, and this printing device is normally disconnected from the main operating mechanism of the machine. A testing device is provided which at each operation is moved to a position adjacent the slip carrying table. If a long bundle slip is in position on the table the testing device will be stopped and will serve to connect the operating device to the auxiliary printing mechanism. If however no such long slip has been placed on the table the auxiliary printing mechanism will not be so connected and will remain inoperative.

Referring to Figs. 4 and 5 it will there be seen that the mechanism includes a series of levers 10 which are moved about a shaft 11 carried by the main frame of the machine. These levers 10 are connected either through the shaft 11 or through a series of nested sleeves 12 surrounding the shaft to segments 13 carrying racks 14. These racks 14 mesh with the pinions 15 and these pinions 15 are connected through a series of nested sleeves 16 to the printing wheels 17. These printing wheels 17 are also shown in Fig. 1 and the mechanism for taking an impression therefrom may also be seen in this figure. A slip carrying table 18 is journaled on a rod 19 and has a depending projection 20 at the lower end of which is an anti-friction roller 21. The main operating shaft 22 of the machine carries a plurality of cam disks, one of which, indicated by a numeral, 23 has a cam groove 24 in which the anti-friction roller rides. A second cam disk 25 also carried by shaft 22 has a cam groove 26 in which rides an anti-friction roller 27 carried by a bell crank lever 28. This bell crank lever 28 is journaled on a rod 29 and has connected to it at its upper end a bar 30 carrying a rack. This rack meshes with a pinion 31 which serves to rotate a feed roller 32. It should be noted

that the pinion 31 and the roller 32 are carried on a shaft which is mounted in the slip table frame. A roller 33 is also mounted in this frame serving to maintain the rack 30 in mesh with the pinion 31. A frame 34 is journaled on the pivot 19 of the slip frame and is normally drawn downward at the left hand by a spring 35. This frame carries a friction feed roller 36.

It will be clear from the above construction that when shaft 22 is rotated the cam groove 24 will serve to rock the slip table 18 around its pivot 19 and throw the slip against the type wheels 17, this being accomplished by the high part 37 of the groove 24. In the further rotation of the shaft 22 the slip table will drop slightly but not enough to withdraw the feed roller 32 from contact with the feed roller 36. The cam groove 26 in the cam disk 25 is so shaped that at this time the friction roller 27 will be rocked upwardly thereby retracting the rack bar 30. This retraction evidently will rotate the feed roller 32 and feed the slip to the left as shown in Fig. 1. A second impression is then taken on the slip due to the high part 38 of the cam groove 24 and thereafter the feed roller 32 is reversely rotated to feed the slip out of the machine. During the last part of the rotation of the shaft 22 the slip table is rocked to its normal downward position. A movable knife 41 co-operates with a stationary knife 42 to sever the voucher from the sales slip, this voucher then drops into a receptacle 43.

The operation as thus far described is that of the machine now on the market and I will now pass to a description of the improvements which I have applied thereto:

Mounted on the shaft 22 for rotation therewith is a gear wheel 47 shown in Figs. 2 and 6. This gear wheel meshes with a gear wheel 48 of an equal number of teeth for half of its width. As shown in Figs. 6 and 7 part of the teeth are only half the width of the remaining part, this cutaway portion being indicated by the numeral 49. Directly above the gear 48 is a pinion 50 the teeth of which are of one half the width of the teeth of gear 48 and the pinion is so positioned as to be directly over the cutaway portion 49. It will be evident that the pinion 50 will rotate as long as the wide teeth of gear 48 are in mesh therewith but will cease rotation when the cutaway portion 49 reaches the teeth of pinion 50. To lock pinion 50 in position while the cutaway portion 49 is passing thereunder I have provided a Geneva stop arrangement indicated generally by the numeral 51. The points of the stop are adapted to be released when the usual depression 52 passes thereunder and to be relocked when the depression 53 reaches the pinion. The pinion 50 is arranged to be given a complete rotation

during the first half of the rotation of shaft 22 and to remain stationary during the last half of said rotation.

The shaft carrying the pinion 50 is indicated by the numeral 54 and this shaft also carries an arm 55 shown in Figs. 2 and 3 having extensions 56 and 57. These extensions are adapted respectively to engage and operate friction rollers 58 and 59. The roller 58 is carried by a slide 60 which is supported and guided by a larger slide 61 this larger slide also carrying the roller 59. A rod 62 is connected at its upper end to the slide 60 and passes through a hole in the slide 61 ending in a knob 62^a under said plate. I also provide a slide 64 on which is fastened a projection 65. The slide 60 is connected through the pin and slot connection best shown in Fig. 1^a to an arm 66 mounted on a sleeve 67 on the shaft 68. At the other end of this sleeve is an arm 69 (see Fig. 2) which is connected by a pin to an arm 70. A spring 71 surrounds the arms 69 and 70 and serves to maintain a lug 72 on the latter in contact with the arm 69. Arms 69 and 70 and the slide 60 operating them constitute what I have termed a testing device in as much as the slide is raised at each operation thereby depressing the arms until the projection 73 may pass through a slot 74 in an extension of the slide table. A pivoted arm 77 is journaled on the pin which supports the anti-friction roller 59 and which is carried by the slide 61. This arm 77 has a projection 78 adapted under certain conditions to contact with the lug 65 on the slide 64. The slide 64 is connected by a pin and slot connection to a arm 79 shown in Figs. 2^a and 2^b which arm 40 is carried by the shaft 68 previously referred to. At the other end of the shaft 68 is an arm 80 carrying an auxiliary printing device 81^a. This printing device is normally in the position shown in Fig. 2^a.

45 The operation of these parts is as follows: It will be remembered that the shaft 54 carrying the peculiarly shaped arm 55 is given a complete rotation during the first half of every operation of the machine. Fig. 2 shows the normal position of this arm 55 and it will be seen that the extension 56 of said arm is in position to engage and elevate the slide 60 through the anti-friction roller 58. The elevation of the slide 60 will 55 evidently rock the testing device 69 and 70 around the shaft 68 and will finally bring the projection 73 into contact with the long bundle slip or if no slip has been placed in the machine will move the projection 73 through the slot 74. When the slide 60 is raised the rod 62 is of course raised with it and this serves to elevate the slide 61 as the lug 62^a is under said slide. When the slide 61 has been slightly elevated the extension 57 of the arm 55 will engage under

the anti-friction roller 59 of the slide 61. During the further rotation of arm 55 both slides will be driven directly from this arm until the position shown in Fig. 3 is nearly reached. At this time the forward or operating edge of the extension 56 passes from under the anti-friction roller 58 and this is timed to occur just when the projection 73 of the testing device reaches the plane of the slip table. If the slip has been inserted the testing device will be stopped but this will stop only the slide 60 and will not stop the slide 61 as the slide 61 is at this time independently driven by the projection 57. The further motion of arm 55 will therefore 70 continue to elevate the slide 61 and the arm 77 mounted on this slide will engage the anti-friction roller 58 with its upper edge. This upper edge is oblique as will be seen and so is well adapted to rock around its 75 pivot at 59 to the position shown in Fig. 3. This rocking is against the tension of the small spring 81 and serves to bring the projection 78 under the lug 65 carried by the slide 64. It will be remembered that this 80 slide is connected to the printing device 81^a and it will be evident that when the projection 78 engages 65 that the further elevation of slide 61 will carry slide 64 up with it and thereby cause the printing device to be 85 depressed to the position shown in Fig. 2^b to make an impression on the bundle ticket. If however no slip has been placed on the table the projection 73 will not be stopped but will be allowed to pass some distance 90 into the slot 74. This last part of the elevation of slide 60 will be caused by the spring 82 which surrounds rod 62 and which is tensioned by the slide 61 in its upward motion. When the slide 60 has moved to its 95 highest position it will be stopped in a position slightly elevated above that in which it came to rest when the slip had been inserted and in such case the camming of arm 77 will not take place until its projection 78 has 100 passed above the lug 65 on the slide 64 so that in this case no operation of the auxiliary printing device will be made. It will be seen that this mechanism provides in a 105 very satisfactory manner for the functions desired; that is, to produce the impressing movement of the printing device 81^a only when a slip has been inserted on the slip table.

110 It will be seen from the above that the auxiliary printing device 81^a and that portion of the slip table 18 with which it contacts form members of a printing couple, by which phrase it is meant to cover broadly any style of printing or recording devices 115 either member of which is brought into contact with the other.

120 The spring 71 surrounding the testing device is for the purpose of preventing puncturing of the slip by the projection 73. 130

When the slip is in place and the projection 73 stopped the further motion of slide 61 will tension spring 82 and this of course produces additional pressure of the projection 73 on the paper and if the testing device was composed of a rigid arm it might well puncture the slip. With the provision of the spring however between the arms 69 and 70 the arms may bend at their common 10 pivot and thereby prevent the chance of such puncturing of the slip.

The auxiliary printing device is inked by a mechanism shown best in Figs. 2^a and 2^b. Journalled on the pin 91 which is carried 15 by the arm 92 supported by a main piece 93 is an arm 94 carrying an ink pad 95. The length of the arm is such that the pad will ink the type of the printing device 81^a. Connected to the arm 94 is a second arm 96 20 which depends in front of an anti-friction roller 97 carried on the supporting arm 80. The arm 94 has also a projection 98 which is adapted to be engaged by a latch 99, this latch being pivoted at 100 and drawn normally in one direction by a spring 101. The latch 99 has an arm 102 projecting at right angles therefrom over the anti-friction roller 97. When the arm 80 is rocked around its 25 pivot 68 the anti-friction roller 97 will engage the depending arm 96 and rock the inking arm 94 to the position shown in Fig. 2^b. The arm is held in this position by the latch 99 which under the tension of its spring 101 moves in front of the projection 30 98 of the arm 94. When the arm 80 returns to its normal vertical position the anti-friction roller 97 will engage the right angle extension 102 of the latch 99 and rock it against the tension of the spring 101 around 35 its pivot 100. This will withdraw the latch 99 from in front of the projection 98 and the spring 104 will then depress the ink pad carrying the arm 94 to the position shown in Fig. 2^a.

45 While the form of mechanism here shown and described is admirably adapted to fulfil the objects primarily stated, it is to be understood that it is not intended to confine the invention to the one form of embodiment herein disclosed, for it is susceptible of embodiment in various forms all coming within the scope of the claims which follow.

What is claimed is as follows:

- 55 1. In a machine of the class described, the combination with an operating mechanism, of a printing couple normally disconnected from the operating mechanism, and means controlled by the presence of an article to be marked for connecting a part of said printing couple to the operating mechanism.
- 60 2. In a machine of the class described, the combination with an operating mechanism, of a printing device and connections normally disconnected from said operating

mechanism, and means dependent for operation on the presence of an article to be marked for connecting said device and operating mechanism.

3. In a machine of the class described, the combination with an operating mechanism, of a printing device and connections normally disconnected from said mechanism, a movable part moved by said operating mechanism at each operation, and means controlled by the presence of an article to be marked for connecting said movable part to said printing device connections. 75

4. In a machine of the class described, the combination with an operating mechanism, of a stamping means adapted to be operated from said mechanism, but normally disconnected therefrom, a testing device, and means controlled thereby for connecting said stamping means operatively to said operating mechanism. 80

5. In a machine of the class described, the combination with a printing mechanism, and an operating mechanism arranged to operate said printing mechanism at each operation 90 of the machine, of an auxiliary printing mechanism normally disconnected from said operating mechanism, and means controlled by the presence of an article to be marked for connecting said auxiliary mechanism for 95 operation by the operating mechanism.

6. In a machine of the class described, the combination with an operating mechanism, and a printing mechanism operated thereby, of an auxiliary printing mechanism, normally out of operative connection with said operating mechanism, and means having its 100 operation determined by the presence of an article to be marked, for establishing a connection between said operating mechanism and said auxiliary printing device.

7. In a machine of the class described, the combination with an operating mechanism, and printing mechanism operated thereby, of an auxiliary printing mechanism normally out of operative connection with said 110 operating mechanism, a testing device, and means controlled thereby for establishing an operative connection between said operating mechanism and said auxiliary print- 115 ing mechanism.

8. In a machine of the class described, the combination with an operating mechanism, and printing mechanism controlled thereby, of an auxiliary printing mechanism normally out of operative connection with said 120 operating mechanism, a testing device adapted to be stopped by the article to be marked, and means operating only when the testing device has been so stopped for 125 connecting the auxiliary printing mechanism to the operating mechanism.

9. In a machine of the class described, the combination with a stamping device, of an 130 operating mechanism therefor, and means

controlled by the presence of an article to be marked for connecting the stamping device to the operating mechanism.

10. In a machine of the class described, the combination with an operating mechanism, and a regular printing mechanism actuated by said operating mechanism at each actuation thereof, of an auxiliary printing mechanism, devices actuated from said operating mechanism, but normally disconnected therefrom for operating said auxiliary printing mechanism, a device for testing the presence or absence of an article to be marked, and means controlled by said testing device for connecting said operating mechanism to said auxiliary printing mechanism.

11. In a machine of the class described, the combination with a stamping device, of means for operating same normally disconnected from said stamping device, and means for connecting said operating means to said stamping device, controlled by the article to be marked.

25. 12. In a machine of the class described, the combination with a printing mechanism, of an operating mechanism therefor, a stamping device normally disconnected from said operating mechanism, and means controlled by the article to be marked for connecting said stamping device to said operating mechanism.

35. 13. In a machine of the class described, the combination of a stamping device, of an operating mechanism normally disconnected therefrom, a testing device given an excursion at each operation and arranged to be stopped by the article to be marked, and means controlled by said testing device and operative only when the same has been stopped, for connecting said operating mechanism to said stamping device.

45. 14. In a machine of the class described, the combination with an operating mechanism, of a printing couple normally disconnected from the operating mechanism, a testing device and means controlled by the testing device for connecting a part of said printing couple to the operating mechanism.

50. 15. In a machine of the class described, the combination with an operating mechanism, and a stamping device arranged to be operated thereby, of means for connecting and disconnecting said stamping device from said operating mechanism, and a testing device controlling said connecting and disconnecting means.

60. 16. In a machine of the class described, the combination with an operating mechanism, of a printing couple normally disconnected from the operating mechanism, a flexible testing device and means controlled by the testing device for connecting a part of said printing couple to the operating mechanism.

17. In a machine of the class described, the combination with a stamping device, and an actuating slide therefor, an operating slide, a testing device, and means controlled by said testing device for producing and destroying an operative relation between said operating and actuating slides.

70. 18. In a machine of the class described, the combination with a pivoted stamping device, of a pivoted inking device therefor, having provisions allowing its movement by said stamping device, means for latching the inking device after it has been moved, and provisions carried by the stamping device for tripping the latching means.

80. 19. In a machine of the class described, the combination with an operating mechanism, and a stamping mechanism constructed to be actuated by said operating mechanism but normally disconnected therefrom, a testing device actuated by said operating mechanism, and given a constant excursion thereby if unobstructed, and means controlled by said testing device when obstructed only for connecting said operating and stamping mechanisms.

85. 20. In a machine of the class described, the combination with an operating mechanism, a testing device actuated thereby, a stamp and actuating devices therefor, and means controlled by the testing device for bringing the actuating devices for the stamp into position to be engaged by the operating mechanism.

90. 21. In a machine of the class described, the combination with an operating mechanism, a testing device actuated thereby, a stamp and actuating devices therefor, and means controlled by the testing device for bringing the actuating devices for the stamp into a position to be engaged by the operating mechanism, the said means allowing a movement of the stamp actuating devices independent of the testing device.

95. 22. In a machine of the class described, the combination with an operating mechanism, a testing device actuated thereby, a stamp/actuating devices for said stamp carried by the testing device, and having an independent movement thereon, and means controlled by the operating mechanism for first operating the testing and actuating devices together and then the latter devices independently.

100. 23. In a machine of the class described, the combination with a type carrier, of a second type carrier, a movable table for supporting a slip, and an operating mechanism for moving the table to take an impression upon the slip from one of the type carriers and for moving the other type carrier to impress a character upon the slip.

115. 24. In a machine of the class described, the combination with a type carrier, of a second type carrier, a movable table for sup-

porting a slip, an operating mechanism for moving the table to take an impression upon the slip from one of the type carriers, and means controlled by the presence of the 5 slip for connecting the other type carrier to the operating mechanism so as to move the last mentioned type carrier to impress a character upon the slip.

25. In a machine of the class described, 10 the combination with a plurality of type carriers, a movable table for supporting a slip, an operating mechanism for moving the table to take an impression upon the slip from one of the type carriers, and a testing device operated by the operating mechanism and working in conjunction with the 15 slip for connecting another of the type carriers to the operating mechanism so that the latter type carrier may be actuated thereby, 20 to impress a character upon the slip.

26. In a machine of the class described, the combination with an operating mechanism, of a printing couple the members of 25 which are normally separated, means for bringing the members of the couple together to impress upon a slip any suitable data, the said means being normally disconnected from the operating mechanism, and a device operated by the operating mechanism for 30 testing the presence of the slip, which device controls the connection to the operating mechanism of the means for bringing the members of the couple together.

27. In a machine of the class described, 35 the combination with an operating mechanism, of a printing couple the members of which are normally separated, a device actuated by the operating mechanism for testing the presence of an article to be marked 40 by the printing couple, and means connected to the testing device and movable independently thereof by the operating mechanism for bringing the members of the print-

ing couple together when the article is present so as to mark said article. 47

28. In a cash register, the combination with a main printing device, of an auxiliary printing device in close proximity thereto, both printing devices adapted to print upon a paper slip of sufficient length to be engaged thereby, and means for disabling the auxiliary printing device when the machine is operated in connection with a slip of insufficient length. 50

29. In a machine of the class described, 55 the combination with a main printing mechanism, of an auxiliary printing mechanism, and means, controlled by the length of the article to be printed upon, for operably connecting the auxiliary printing mechanism with the main printing mechanism. 60

30. In a machine of the class described, the combination with a main printing mechanism, of an auxiliary printing mechanism, and means controlled by the position 65 of the strip to be printed upon by the main printing mechanism, for determining whether the auxiliary printing mechanism will be operated.

31. In a machine of the class described, 70 the combination with a main printing mechanism and an auxiliary printing mechanism, adapted to simultaneously print respectively upon the two ends of a slip, of means for feeding the slip so that the 75 main printing mechanism may print intermediate the previously printed parts of the slip, the auxiliary printing mechanism rendered inoperative by the feeding movement of the slip. 80

In testimony whereof I affix my signature in the presence of two witnesses.

JOSEPH P. CLE M.
